UNITED STATES PATENT OFFICE.

JOHN H. D. PETERSEN AND JOHN W. WILSON, OF CHICAGO, ILLINOIS, ASSIGNEES TO
LINK-BELT COMPANY, OF CHICAGO, ILLINOIS, A CORPORATION OF ILLINOIS.

SHAKER CONVEYER.

Application filed July 12, 1926. Serial No. 121,795.

Our invention relates to a feeding device for excavating or conveying machinery and particularly to a feeder for shaker or reciprocating conveyers. One object of our invention is the provision of feeding means for use with a feeding conveyer, whereby a conveyer may automatically feed itself or pick up the material to be conveyed. Another object is the provision of a combined excavating and conveying member whereby material may be fed to a reciprocating conveyer in response to the reciprocation of the conveyer. Another object is the provision of means for extending such a conveyor and feed member, in order to permit prolonged feeding without frequent adjustment. Another object is the provision of articulating means for permitting lateral movement of the feeder and conveyer and of relative movement, lateral and otherwise, of the feeder and the various sections of the conveyer.

Other objects will appear from time to time in the course of the specification and claims.

We illustrate our invention more or less diagrammatically in the accompanying drawings, wherein—

Figure 1 is a vertical longitudinal section of a typical conveyer;

Figure 2 is a similar section, in continuation of Figure 1, illustrating the feeding member as applied to the conveying member;

Figure 3 is a plan view;

Figure 4 is a bottom plan view, with parts cut away, showing the intersection between the conveyer section and the feeding member;

Figure 5 is a section on the line 5—5 of Figure 4;

Figure 6 is a section on the line 6—6 of Figure 5;

Figure 7 is an enlarged detail view of the feeding mechanism; and

Figure 8 is a section taken on the line 8—8 of Figure 2.

Like parts are indicated by like characters throughout the specification and drawings.

Whereas we do not wish to limit ourselves to the particular employment of the feeding member herein shown, or to any particular conveyer, it is herein illustrated as employed with a reciprocating or shaking conveyer of the type wherein the conveyer is reciprocated in opposite directions at different speeds, for example, with a slow forward movement and a rapid rearward movement. Referring for example to Figures 1 and 2, A indicates the

floor and A¹ the roof of a mine tunnel or passage. A² is a transverse passage containing for example the tracks A⁴ adapted to guide any suitable conveying member or car A⁵.

B is a conveyer trough or chute which may be reciprocated for example upon the rollers B¹, which rest upon track members B² and support the upper track members B³ upon the trough B.

C diagrammatically illustrates any suitable reciprocating means for said trough, including the crank arm C¹.

Referring to Figures 2 and 3, we illustrate the trough B as having secured to the forward end of the forward section of the feeder member generally indicated as X. It will be understood that we may employ any suitable number of trough sections B, additional sections being inserted as the work progresses.

The securing means between the feeding member and the end of the trough B shown in detail in Figures 4, 5 and 6, are as follows: Secured to the bottom of the trough B is a reinforcing plate D which terminates at the ends in eyelets or expanded portions D¹ apertured as at D² to receive the members D³. The members D³ are shouldered as at D⁴ and continue as reduced portions D⁵ screw threaded as at D⁶. D⁷ are lock nuts, which serve to draw the members D³ against the rear face or edge of the eyelet D¹.

The feeder member, generally indicated as X, includes a lower trough E. The feeding member consists preferably of two separate troughs E and E¹, the upper trough E¹ being in slidble relation with the lower trough E, there being no fixed connection between the trough E and the conveyer section B. At the rear end of the trough E is a reinforcing plate E² spaced beneath which is the bottom plate E³. Between E² and E³ may be any suitable spacer or filler E⁴ the assembly being bolted together for example by the bolts or rivets E⁵. Passing through the bottom of the trough E and through the plates E² and E³, is any suitable pivot member or pin E⁶ provided with a washer E⁷ and a securing pin E⁸.

Pivoted for rotation about it in a horizontal plane, and in part contained between the plates E² and E³ is the arm E⁹ having at its ends shoulders E¹⁰ beyond which outwardly project the cylindrical portions E¹¹. Pivoted upon each such cylindrical member E¹¹ is the connecting member D⁹.

which is confined for example by the washer E¹³ and the securing pin E¹⁴.

As regards the feeding member proper we may provide any suitable means for advancing the upper trough E¹ in relation to the lower trough E. We may employ any suitable rack and pinion connection between the two including for example the rack G on one member and the pinion G¹ on the other member and the lever G² adapted to control them.

The lower trough E of the feeder is supported upon the ground in the following manner: The member J is a transverse slide or runner which engages the ground and permits easy lateral movement of the feeding member. The trough E is supported thereupon for example by means of the downwardly depending members J¹ which are in slidable engagement with the shoe J. When the feeding member is in any given fixed position the member J serves as a stationary support across which slide the members J¹.

Articulating means as employed between the conveyer B and feeder member X may be used between the trough sections B as shown in Figure 3.

It will be realized that whereas we have described and shown a practical and operative device that nevertheless many changes might be made in the size, shape, number and disposition of parts without departing from the spirit of our invention. We therefore wish our description and drawings to be taken as in a broad sense illustrative and diagrammatic rather than as limiting us to our specific showing.

The use and operation of our invention are as follows:

Reciprocating conveyers of the type herein shown are already known in the art, namely, conveyers which may be reciprocated at different velocities in opposite directions in order to convey material fed to them. Such conveyers may be employed for many purposes and may for example be employed in mining. Such a conveyer when so employed may be advanced from a given location by the insertion of additional conveyer sections as the shaft is lengthened, all such sections forming a single conveyer, reciprocated from a single power source. The material to be conveyed may be shot down from the end of the shaft or otherwise accumulated and is generally divided into lumps and particles of varying size. Upon the forward end of the conveyer is mounted a feeding member which is adapted to be thrust by the forward movement of the conveyer into the pile of material to be conveyed. The slow rearward movement of the feeding member conveys away the material received upon it as a result of the rapid forward thrust.

As the face of the material being fed recedes, the upper trough is advanced in rela-

tion to the lower, until it has advanced to such a distance that it is necessary to withdraw it and to insert a new section of the conveyer B.

In operating against a laterally extended face, or along a tortuous passage it is important that the conveyer as a whole be articulated, and even more important that the feeding member at the end of the conveyer be articulated for free lateral movement as well as for movement about a vertical pivot. Thus the entire assembly may be advanced along a crooked passage and up and down various floor levels and the feeding member at the end of the conveyer may be swung laterally to feed from a face of considerable width. We have provided a peculiarly flexible and robust articulating means for the feeder and conveyer assembly herein described and shown. In order to permit the easy lateral movement of the feeding section we provide a supporting ground contacting shoe J which serves as a runner to support the feeder and to permit it to be swung about a vertical pivot. During the normal operation of conveyer and feeder the feeder can reciprocate freely in relation to the runner J, with which it is placed in slidable engagement by means of the downwardly extending supporting members J¹.

We claim:

1. In a self feeding conveyer, a conveyer trough and means for imparting to it a conveying reciprocation, a feeding member at the end of said trough, an arm pivoted to said trough, intermediate its ends, for rotation about a generally vertical axis, connecting members extending from the ends of said arm to said feeding member and rotatable about the ends of said arm.

2. In a self-feeding conveyer, in combination, a generally horizontal conveyer trough and means for imparting to it a differential conveying reciprocation, and a digging and feeding member secured thereto and adapted to move in unison with it and to deliver material directly thereto, said digging member being mounted, in relation to said trough, to permit its rotation about both horizontal and vertical axes.

3. In a self-feeding conveyer, an articulated conveyer trough and means for imparting to it a conveying reciprocation, a feeding member at the receiving end of said trough, an arm pivoted to said trough, intermediate the ends of such arm, for rotation about a generally vertical axis, connecting members extending from the ends of said arm and rotatable thereabout, and a feeding member associated with said connecting members.

Signed at Chicago, in the county of Cook and State of Illinois, this 8th day of July, 1926.

J. W. WILSON.
JOHN H. D. PETERSEN.
